UNITED STATES PATENT OFFICE.

WILLIAM S. WITTEN, OF CHICAGO, ILLINOIS.

LOCK AND LATCH.

Application filed May 16, 1921. Serial No. 470,206.

To all whom it may concern:

Be it known that I, WILLIAM S. WITTEN, a citizen of the United States, and a resident of Chicago, in the county of Cook and State 5 of Illinois, have invented certain new and useful Improvements in Locks and Latches, of which the following is a specification, reference being had to the accompanying drawings.

10 My invention relates to locks and latches of the type comprising a pendulous latch member normally held in operative position by gravity, and has for its object to provide certain improvements in the devices for 15 supporting the latch member and for moving it out of operative position, and also to provide means for locking the latch member in operative position so that a key will be required to unlock the door to which 20 the latch is applied from the side opposite that at which the latch is mounted. I accomplish this object as illustrated in the drawings and hereinafter described. What I believe to be new is set forth in the claims.

25 In the accompanying drawings,

Fig. 1 is a side elevation of part of a door and a door jamb, illustrating my improved latch;

Fig. 2 is a detail, being an enlarged vertical section on line 2—2 of Fig. 3;

Fig. 3 is a partial horizontal section on line 3—3 of Fig. 1;

Fig. 4 is a perspective view of the latch removed from the frame in which it is mounted;

Fig. 5 is a partial vertical section on line 5—5 of Fig. 3; and

Fig. 6 is a perspective view illustrating the locking device by which the latch bolt 40 is locked in operative position.

Referring to the drawings,—7 indicates the door and 8 the door jamb, the latter being preferably provided with a keeper plate 9 having an inclined lip 10 which 45 operates in the usual way to move the latch bolt out of operative position when the door is being closed. The keeper plate is provided with a hole 11 to receive the latch bolt when the same is projected and the door 50 is closed.

As best shown in Fig. 4, the latch member comprises a shank 12 which at its lower end is provided with a cross-head 13, one end portion 14 of which constitutes the latch bolt, the other end portion 15 thereof serving to effect the movement of the latch bolt

into operative position by gravity, and also to resist strains tending to twist the shank 12. At the upper end of said shank is a pivot bearing 16 which is adapted to receive a pivot pin 17 from which the latch member is suspended so as to swing freely. From the pivot bearing 16 an operating arm 18 extends diagonally upward at the same side as the end portion 15 of the cross-head 60 13, which arm provides a convenient means of moving the latch bolt out of operative position by hand, and also aids in causing it to move into operative position by gravity.

The latch member is mounted in a frame 70 19 having side plates 20, 21 spaced apart a sufficient distance to receive the latch. These side plates are made T-shaped to correspond with the shape of the shank and cross-head, as shown in Fig. 1, and the lower portions 75 thereof are fixedly connected together by integral studs 22, 23 at diagonally-opposite corners, as shown in Figs. 2 and 3. The upper end portions of said plates are connected by the pivot 17 and are held properly spaced apart by the pivot bearing 16. The frame 19 is secured to a door near the outer edge thereof, its upper end being secured by the pivot 17, which is preferably in the form of a bolt or screw, while the 80 lower portion of said frame is secured to the door by bolts or screws 24, 25. The screw 25 is arranged in advance of the lower portion of the shank 12 and serves as a stop to limit the extent to which the latch bolt 85 projects when in operative position. For moving the latch bolt out of operative position by hand from the opposite side of the door I provide a pin 26, the inner end of which is secured to the upper portion of 90 the stem 12, as best shown in Figs. 1 and 4, said pin projecting through a slot 27 in the inner plate 21 and through a corresponding slot 28 provided in the door. Preferably a slot 29 similar to the slot 27 is also provided 95 in the plate 20 so that the pin 26 may be reversed in case it should be desired to apply the latch to the opposite side of the door.

For locking the latch bolt in operative position so that a key will be required to 100 open it from the side of the door opposite to that to which it is applied, I provide a locking dog 30 which is mounted upon and keyed to a rock-shaft 31 fitted in the lower portion of the frame 19 adjacent to the lower 110 end portion of the shank 12 and at the opposite side thereof from the screw 25, as

shown in Figs. 1 and 2. The dog 30 is provided with a sleeve 32 which fits upon the shaft 31 and is non-rotatably secured thereto, preferably by means of a set-screw 33. Said dog is also provided with an upwardly-projecting thumb piece 34 by which it may be moved into or out of operative position by hand, and with a stop plate 35 which is adapted to rest on the upper margins of the plates 20, 21 when the dog 30 is in operative position, as shown in Figs. 1 and 2. The rock shaft 31 also carries a head or disc 36 which is non-rotatably secured upon the inner end thereof and is adapted to be engaged by the usual pin 37 of a cylinder lock 38 of any approved type, which is mounted in the door with its key-hole at the side thereof opposite that on which the latch is mounted. The arrangement is such that when the pin 37 is caused to revolve about the axis of the lock 38 by means of a key inserted in said lock it will engage the head 36 and through it will rock the shaft 31 and correspondingly move the dog 30. By this construction, when the door is closed, by means of the key the latch bolt 14 may be locked in its operative position by turning the dog 30 down to the position shown in Fig. 2, so that it engages the edge 30 of the shank 12 and prevents it from swinging away from the screw 25. The latch bolt 14 will, therefore, be held in its operative position. This, however, will not prevent the latch bolt from being released by any person at the opposite side of the door, as the dog 30 may be moved out of operative position by means of the thumb piece 34 which is accessible from that side. In like manner the dog 30 may be moved into operative position from one side of the door by means of the thumb piece, or it may be similarly moved from the opposite side of the door by means of a key. When the dog 30 is thrown back out of operative position the latch bolt may be swung out of operative position by means of the pin 26 by a person on the opposite side of the door.

By the construction described I provide a very simple but substantial latch and lock which cannot easily get out of order, and which may readily be applied to either side of a door in such manner that when the locking device is not in operative position the latch may be actuated from either side of the door, but which may also be locked so that while it may be unlocked without a key from that side of the door on which it is mounted it can be unlocked from the other side only by means of a key. It will be noted that if the latch is applied to the opposite side of the door from that shown in the drawings it is necessary only to reverse the pin 26 and the position of the dog 30 and head 36 on the rock-shaft 31. By then inserting the cylinder lock 38 from the op-

posite side of the door its actuating pin 37 will be in operative relation to said head.

What I claim as my invention and desire to secure by Letters Patent, is—

1. A latch comprising a frame adapted to be secured to one side of a door, a shank pivotally mounted at its upper end in said frame, a latch bolt at the lower end of said shank and normally projecting beyond one end of said frame, a pin connected with and projecting laterally from said shank adjacent to the pivot thereof, and extending through a slot in the door to which the latch is applied, for moving said latch bolt out of operative position, and an operating arm connected with the upper end of said shank. 70

2. A latch comprising a frame adapted to be secured to one side of a door, a shank pivotally mounted at its upper end in said frame, a latch bolt at the lower end of said shank and normally projecting beyond one end of said frame, a pin connected with and projecting laterally from said shank adjacent to the pivot thereof, and extending through a slot in the door to which the latch is applied, for moving said latch bolt out of operative position, and an operating arm connected with the upper end of said shank and lying in substantially the same plane 80

as the shank. 95

3. A latch comprising a frame adapted to be secured to one side of a door, a shank pivotally mounted at its upper end in said frame, a latch bolt at the lower end of said shank and normally projecting beyond one end of said frame, means connected to said shank whereby said latch bolt may be moved out of operative position, a locking member mounted in said frame adjacent to said shank and adapted to rock into or out of engagement therewith, and key-operated means for rocking said member from the side of the door opposite that to which the latch is applied. 100

4. A latch comprising a frame adapted to be secured to one side of a door, a shank pivotally mounted at its upper end in said frame, a latch bolt at the lower end of said shank and normally projecting beyond one end of said frame, means whereby said latch bolt may be moved out of operative position, a rock-shaft mounted in said frame adjacent to said shank, a locking dog non-rotatably mounted on said rock-shaft and movable by the rocking thereof into or out of engagement with said shank, and key-operated means mounted in the door and operatively associated with said dog for actuating the same. 110

5. A latch comprising a frame adapted to be secured to one side of a door, a shank pivotally mounted at its upper end in said frame, a latch bolt at the lower end of said shank and normally projecting beyond one end of said frame, means whereby said latch 120

bolt may be moved out of operative position, a rock-shaft mounted in said frame adjacent to said shank, a locking dog mounted on said rock-shaft and movable by the rocking thereof into or out of engagement with said shank, key-operated means mounted in the door and having an actuating pin, and a head carried by said rock-shaft and adapted to be engaged by said pin for moving said dog into or out of operative position.

6. A latch comprising a frame adapted to be secured to one side of a door, a shank pivotally mounted at its upper end in said frame, a latch bolt at the lower end of said shank and normally projecting beyond one end of said frame, means whereby said latch bolt may be moved out of operative position, a rock-shaft mounted in said frame adjacent to said shank, a locking dog mounted on said rock-shaft and movable by the rocking

thereof into or out of engagement with said shank, key-operated means mounted in the door and operatively associated with said dog for actuating the same, and a thumb piece carried by said dog for moving the same into or out of operative position.

7. A latch comprising a frame adapted to be secured to the side of a door, a swinging latch member supported by said frame, a locking member mounted in said frame adjacent to said latch member and adapted to rock into or out of engagement therewith, a cylinder lock adapted to be mounted in the door, and reversible devices associated with said cylinder lock and said locking member for actuating said locking member by means of said cylinder lock, whereby the latch is adapted to be mounted at either side of the door.

WILLIAM S. WITTEN.
